PLUGGING WATER SANDS BY A
HYDRATABLE MATERIALGeorge E. Cannon, Houston, Tex., assignor to
Standard Oil Development Company, a corpora-
tion of Delaware

Application October 17, 1934, Serial No. 748,578

5 Claims. (Cl. 166—21)

This invention relates to improvements in excluding water from oil and gas wells.

In producing oil or gas from a well, water frequently enters the well along with the oil or gas. Production of water in this manner is undesirable and frequently attempts are made to shut off the flow of water by cementing the lower portion of the well or by driving lead wool into the bottom of the well. In shutting off water by the methods commonly in use, it frequently happens that a portion of the oil-bearing stratum is plugged off also and the oil contained in such stratum is lost. In some cases the exact position of the formation which is producing water is not known or is so situated that it is impossible to use the cement or lead wool method for plugging the water off.

It is an object of this invention to plug water-bearing sands encountered in oil wells without affecting the oil-bearing sands.

Other objects would be apparent from the specification and from the accompanying drawing, in which latter the figure is a diagrammatic representation of a preferred apparatus for carrying out the invention.

Referring particularly to the drawing, reference numeral 1 designates the bore of a well into which extends a string of tubing 2. The portion of the tubing 2 protruding from the surface of the earth is provided with a T-shaped coupling 5. The T-shaped coupling 5 is provided with pipes 6, 7, and 8. The tubing 2 extends substantially throughout the length of the bore 1 of the well. The bore of the well pierces strata such as 10 and 11, which are composed of water-bearing sand which flows into the tubing 2 of the well and is delivered with oil and gas from the oil-bearing sand 13.

The water from the water-bearing sands 10 and 11 is prevented from flowing into the bore 1 of the well by pumping into the well as by the pipe 8 a fluid from a suitable source of supply 15 by means of a pump 16. The fluid flows downwardly through the casing 2 to the end of the casing and then it flows upwardly and is delivered through a line 17. The fluid is maintained under sufficient pressure by the pump 16 to cause the fluid to overcome the hydrostatic head of the water in the porous strata 10 and 11 and forces its way into the porous sand permeating the water-bearing strata to the desired extent. The water in the sands 10 and 11 contains soluble inorganic salts such as sodium chloride, calcium chloride, magnesium chloride, and the like. The fluid, on contact with the water in the sand, forms

a solid substance within the interstices of the sand at 20, which plugs the pores of the sand and renders it impervious to water flow.

The fluid used comprises a suspension of a material which swells on contact with water. The base of the fluid is a non-aqueous medium, which preferably is miscible with water. The material is inert physically to oil. The material used may be such hydratable material as hydratable clays, for example bentonite. Gelatin, agar agar, and like material which swell on contact with water can also be used. The hydratable materials can be suspended in any non-aqueous medium such as crude oil, gas oil or the like, but preferably in a medium such as alcohol, glycerine or the like, which is miscible with water. The addition of lime and dispersing agents such as oleic acid may be added to aid in suspending the hydratable material in the non-aqueous medium for convenience in handling the suspension. Other members of the fatty acid series, the soaps of fatty acids, soaps of naphthenic acids and sulfonated naphthenic compounds may be used as dispersing agents for the suspension, if desired.

By way of specific example, the following composition may be cited:

	Per cent by volume
Isopropyl alcohol	84.5
Bentonite	10.0
Lime	5.0
Oleic acid	0.5

In this compound the isopropyl alcohol is the non-aqueous suspending medium, the bentonite is the hydratable material which swells on contact with water, the lime and the oleic acid are suspending or dispersing agents which are added to make the suspension more stable and easier to handle. Either the lime or the oleic acid, or both, may be omitted, and some of the advantages of the invention will be retained.

Another composition comprises:

	Per cent by volume
Gas oil	85
Gelatin	10
Lime	5

The composition is pumped from the reservoir 15 into the well under sufficient pressure to cause the composition to pass into the water-bearing sands 10 and 11, where the colloidal material is wetted by the water present in the sand, and hydration takes place which increases the volume of the solid particles substantially filling the in-

terstices of the sand, as designated at 28, resulting in the permeability of the sand being reduced to such an extent that it is impossible for water to flow from the sand into the well. The portion 5 of the hydratable material which is forced into the oil-producing formation 13 is not hydrated and the particles do not increase in size. When production of oil or gas from the well is resumed, the portion of the suspensesoid which has entered 10 the oil sand is washed out and the permeability of this portion of the sand is not appreciably affected. The hydratable material which has entered the water-producing formations 10 and 11 is trapped due to its having increased in size, resulting 15 in permanently plugging the water-bearing sands 10 and 11.

Various changes may be made within the scope of the appended claims, in which it is desired to claim all novelty inherent in the invention.

20 I claim:

1. A process for plugging off water producing sands in a well producing both oil and water, comprising introducing into the well a suspension in oil of a solid material inert to oil but which 25 swells on contact with water and permitting the suspension to flow into both the oil and water-bearing sands whereby the suspension on contact with the water in the water-bearing sand swells to plug the pores of only the water-bearing sand 30 to form a seal against the further entrance of water into the well.

2. A process for plugging off water producing sand in a well producing both oil and water, comprising introducing into the well a suspension in 35 a non-aqueous medium of a solid material inert to the medium and to the oil which solid material swells on contact with water and permitting the suspension to flow into both the oil and water-bearing sands whereby the material contacts the 40 water in the water-bearing sand and swells to

plug the pores of only the water-bearing sand forming a seal against the further entrance of water into the well.

3. A process for plugging off water-bearing sand in a well producing both oil and water, comprising introducing into the well a suspension in a non-aqueous medium miscible with water of a solid material inert to the oil and to the medium but which swells on contact with water and permitting the suspension to flow into both the oil 10 and water-bearing sands whereby the material contacts the water in the water-bearing sand and swells to plug the pores of only the water-bearing sand to form a seal against the further entrance 15 of water into the well while permitting free flow of oil from the oil-bearing sand.

4. A process for plugging off water producing sand in a well producing both oil and water, comprising introducing into the well a suspension of a hydratable clay in a non-aqueous medium to 20 cause the suspension to flow into both the oil and water-bearing sands whereby the hydratable clay contacts the water in the water-bearing sand and swells to plug the pores of only the water-bearing sand to form a seal against the further entrance 25 of water into the well while permitting free flow of oil from the oil bearing sand.

5. A process for plugging off water producing sand in a well producing both oil and water, comprising introducing into the well a suspension of gelatine in a non-aqueous medium to cause the gelatine to flow into both the water and oil-bearing sands whereby the gelatine contacts the water in the water-bearing sand and swells to plug the pores of only the water-bearing sand 35 to form a seal against further entrance of water into the well while permitting free flow of oil from the oil-bearing sand.
